ARMCHAIR

Jerry Johnson, 3739 S. Rodeo Drive, Malibu, Calif.

Filed Oct. 2, 1962, Ser. No. 71,974

Term of patent 7 years

(Cl. D15—1)

FIG. 1 is a perspective view taken from the front of the armchair showing my new design; and

FIG. 2 is a perspective view taken from the rear aspect thereof.

I claim:

The ornamental design for an armchair as shown.
